UNITED STATES PATENT OFFICE.

DEMETRIUS M. STEWARD, OF CHATTANOOGA, TENNESSEE.

DESIGN FOR AN ARGAND BURNER FOR ACETYLENE GAS.

SPECIFICATION forming part of Design No. 33,503, dated November 6, 1900.

Application filed October 9, 1900. Serial No. 32,554. Term of patent 7 years.

To all whom it may concern:

Be it known that I, DEMETRIUS M. STEWARD, a citizen of the United States, residing at Chattanooga, Tennessee, have invented and produced a new and original Design for an Argand Burner for Acetylene Gas, of which the following is a full, clear, and exact specification.

In the accompanying drawings, Figure 1 is a side elevation of a burner made in accordance with my invention. Fig. 2 is a plan view of the same, while Fig. 3 is a sectional view.

The leading feature of the design is in the external configuration and the shape disclosed by the sectional view. The burner comprises an inner tubular wall A, open at top and bottom, with an outer tubular wall

B of less extent in its length and joined to the inner wall at its upper end, forming a thickened portion, which is provided with a series of vertically-extending recesses c, these being intersected by horizontal passages a and communicating with the space within the inner tube as well as the external air. An annular passage or space is formed between the walls A and B.

What I claim is—

The design for an Argand burner for acetylene gas as herein shown and described. 30

In testimony whereof I affix my signature in presence of two witnesses.

DEMETRIUS M. STEWARD.

Witnesses:

HERMAN FERGER,
T. E. PATTERSON.
